(57) **CLAIM**

I claim the ornamental design for a control panel for laundry appliance, as shown and described.

DESCRIPTION

FIG. 1 is a perspective view of the control panel for laundry appliance according to the present invention.

FIG. 2 is a top plan view of the control panel.

FIG. 3 is a side elevation view of the control panel; and, FIG. 4 is a front elevation view of the control panel.

Applicant makes no claim to the bottom or rear design of the control panel.

The features in broken lines form no part of the claimed invention.
